LOCKING DEVICE

Neil O. Holmsten, New Rochelle, N. Y.

Application December 22, 1949, Serial No. 134,577

3 Claims. (Cl. 70—89)

1

This invention relates to locking devices for use with standard latches of the type commonly used on swinging windows and has for an object to provide a compact locking device of the above type which can be installed readily and is dependable in operation.

Another object is to provide a lock for the above purpose which is spring biased in unlocked position, but is automatically locked upon being pressed into position to secure the latch.

Other objects will be apparent as the nature of the invention is more fully disclosed.

The nature of the invention will be better understood by referring to the following description taken in connection with the accompanying drawings in which certain specific embodiments are shown for purposes of illustration.

In the drawings:

Fig. 1 is a front elevation of a locking device embodying the present invention as applied to a window;

Fig. 2 is a vertical section taken on the line 2—2 of Fig. 1;

Fig. 3 is a horizontal section taken on the line 3—3 of Fig. 1;

Figs. 4 and 5 are sections taken on the lines 4—4 and 5—5 respectively of Fig. 2;

Fig. 6 is a section taken on the line 6—6 of Fig. 1;

Fig. 7 is a front elevation similar to Fig. 1 of a lock illustrating another embodiment of the invention;

Fig. 8 is a vertical section taken on the line 8—8 of Fig. 7;

Fig. 9 is a vertical section taken on the line 9—9 of Fig. 8;

Fig. 10 is a horizontal section taken on the line 10—10 of Fig. 7;

Fig. 11 is a longitudinal section through a lock illustrating a further embodiment of the invention; and

Fig. 12 is a section taken on the line 12—12 of Fig. 11.

Referring to the drawings more in detail the lock is shown in Figs. 1 to 6 as applied to a casement window having a sash 10 carrying suitable panes 11 of glass and closing against a fixed bar 12 forming a part of the window frame. In the form shown a latch 13 is pivoted to a plate 14 attached to the sash 10 by suitable means such as non-removable screws 15 and is provided with a latch finger 16 adapted to engage the bar 12 for clamping the window in closed position, and a handle 17.

The locking device comprises a base plate 20

2

which is attached to the bar 12 by screws 19 and carries a pair of pins 21. A housing 22 is provided with recesses 23 sliding on said pins and spring-pressed outwardly by springs 24 seated around bosses 25 in which said recesses are formed. The outward movement of the housing 22 is limited by pins 26 which slide in recesses 27 in the sides of the pins 21.

The base plate 20 is notched as shown at 30, 10 Fig. 4, to receive the latch finger 16 and one side of the housing 22 formed with a notch 31 to receive the latch finger 16 when in latched position. When the housing 22 is in its retracted position the bottom of the housing clears the 15 latch finger to permit free operation thereof, but when the housing 22 is in its advanced position the notch 31 spans the latch finger and prevents actuation thereof.

The housing carries a lock barrel 33 in which a key actuated lock cylinder 34 is mounted for rotation. The cylinder 34 and barrel 33 are of standard construction and are designed to lock the cylinder to the barrel or release the cylinder by means of a key. The lock cylinder 34 is keyed by a tongue 35 to a bar 36 having apertures 37 to receive the pins 21, said apertures having edges extending through slots 38 in the bosses 25 and engaging beneath shoulders 40 on the pins 21 to lock the bar 36 and housing 22 in advanced position. The bar 36 is spring-biased in locking position by a spring 41 seated between the housing 22 and an ear 42 on the bar 36 and is retracted upon rotation of the lock cylinder 34 when released by the key.

In order to lock the device in latch securing position it is only necessary to press the housing 22 to its advanced position against the force of the springs 24. When the bar 36 passes the shoulders 40 on the pins 21 it snaps into locking position due to the spring 41. The lock cylinder may be of the type which automatically locks to the barrel when rotated into the position indicated above or may be locked thereto by withdrawal of the key. In either case the latch cannot be actuated until the housing has been released by rotation of the lock cylinder to retract the bar 36 from the shoulders 40 of the pins 21 and retracted by springs 24.

In the embodiment of Figs. 7 to 10 the window sash, frame and latch are similar to that above described. The locking device comprises a stud 50 having ears 51 secured to the fixed bar 12 by screws or rivets 52. A housing 53 is provided with side walls 54 which slide on opposite sides of the stud 50. A pin 55, secured in the side

walls 54, extends through a slot 56 to limit the movement of the housing 53. The side walls are formed with notches 57 to span the ears 51 of the stud 50 and with a notch 60 to span the latch finger 16 when the housing is seated against the bar 12.

The housing 53 also carries a lock comprising a barrel 61 fixed to the housing having a key actuated cylinder 62 therein connected to actuate a pawl 63 which is pivoted at 64 to the barrel 61 and enters a notch 65 in the side of the stud 50 when in locking position. The lock barrel, cylinder and pawl are of standard construction in which the pawl 63 is spring-pressed into the notch 65 and is retracted by rotation of the key-actuated cylinder 62. Since the locking mechanism is well known it is not shown in detail herein.

The housing 53 is urged upwardly toward retracted position by a spring 66 seated in a recess 67 therein and seated on the stud 50.

The operation of this locking device is similar to that above described. When released the housing provides clearance beneath the side walls 54 for actuation of the latch finger 16. The housing is automatically locked in its latch engaging position when pressed toward the bar 12 and secures the latch finger until released by turning the key actuated cylinder 62. When so released the housing is forced into retracted position by the spring 66.

In the embodiment of Figs. 11 and 12 a pivoted arm 70 is adapted to contact and secure the latch when depressed. The arm 70 is pivoted at 71 to a housing 72 which is attached by screws 73 to a base plate 74 having ears 75 receiving screws or rivets for attachment to the bar 12 of the window frame. The arm 70 is urged upwardly by a spring 76 and carries a shoulder 77 to be engaged by an arm 80 for locking the arm 70 in its lower position.

The arm 80 is attached to the end of a key-actuated cylinder 81 of a lock barrel 82 fixed in the housing 72. The arm 80 is biased in locking position by a spring 83.

In this embodiment the arm 70 is automatically locked in its lower position when pressed down manually and is releasable by turning the lock cylinder 81 when released by the key. The device is so positioned that the latch finger 16 passes beneath the arm 70 when in raised position, but is engaged and secured by the arm 70 when the arm is in its lower locked position.

Although specific embodiments have been shown the invention may be applied to various uses and adaptations as will be apparent to a person skilled in the art.

What is claimed is:

1. A locking device for a movable member closing against a fixed frame and carrying a latch finger swingable over said frame about an axis normal thereto for latching said movable member to said frame, said locking device comprising a pin fixed to said frame with its axis normal thereto, a housing slidable axially on said pin, stop means limiting the movement of said housing on said pin between retracted and advanced positions, said housing having a recess to receive and secure said latch finger when in advanced position and having a clearance to permit said

5 latch finger to swing thereunder when in retracted position, a shoulder on said pin, a latch member carried by said housing engaging said shoulder to latch said housing in advanced position, and a lock cylinder mounted in said housing and connected to actuate said latch member for releasing said housing for sliding on said pin to retracted position.

2. A locking device for a movable member closing against a fixed frame and carrying a latch finger swingable over said frame about an axis normal thereto for latching said movable member to said frame, said locking device comprising a pin fixed to said frame with its axis normal thereto, a housing slidable axially on said pin, stop means limiting the movement of said housing on said pin between retracted and advanced positions, said housing having a recess to receive and secure said latch finger when in advanced position and having a clearance to permit said latch finger to swing thereunder when in retracted position, a shoulder on said pin, a latch arm carried by said housing engaging said shoulder to latch said housing in advanced position, a lock cylinder mounted in said housing and rotatable, when unlocked, about an axis parallel to said pin, spring means biasing said latch arm to latching position against said shoulder and means connecting said cylinder to retract said latch arm for releasing said housing for sliding on said pin to retracted position.

3. A locking device for a movable member closing against a fixed frame and carrying a latch finger swingable over said frame about an axis normal thereto for latching said movable member to said frame, said locking device comprising a plate attached to said frame having a recess to permit latching movement of said finger over said frame, a pin attached to said plate, with its axis normal thereto, a housing slidable axially on said pin, stop means limiting the movement of said housing on said pin between retracted and advanced positions, said housing having a recess to receive and secure said latch finger when in advanced position and having a clearance to permit said latch finger to swing thereunder when in retracted position, a shoulder on said pin, a latch member carried by said housing engaging said shoulder to latch said housing in advanced position, and a lock cylinder mounted in said housing and connected to actuate said latch member for releasing said housing for sliding on said pin to retracted position.

NEIL O. HOLMSTEN.
